UNITED STATES PATENT OFFICE.

GEORGE E. WAGNER, ROBERT REX DOWNE, AND ROBERT M. DOWNE, OF BEAVER FALLS, PENNSYLVANIA, ASSIGNEES TO KEYSTONE DRILLER COMPANY, OF BEAVER FALLS, PENNSYLVANIA, A CORPORATION OF PENNSYLVANIA.

EXCAVATING SCOOP.

Application filed October 17, 1919. Serial No. 331,268.

To all whom it may concern:

Be it known that we, GEORGE E. WAGNER, ROBERT R. DOWNE, and ROBERT M. DOWNE, citizens of the United States, residing at 5 Beaver Falls, in the county of Beaver and State of Pennsylvania, have invented a new and useful Excavating Scoop, of which the following is a specification.

This invention has reference to excavating 10 scoops, and its object is to provide an excavator or ditcher scoop capable of digging narrow or wide trenches and by means of which the excavated material may be deposited in containers of low altitude.

15 In accordance with the invention, which is assumed to be attached to a suitable excavating machine, there is provided a swinging boom carrying at its outer end a structure, which may be termed a ditcher stick 20 in normally pendant relation to the boom although capable of being moved into other relations thereto, and this stick carries a ditcher scoop pivotally hung on the ditcher stick to rock on a substantially horizontal 25 axis, which axis is located at approximately the center of gravity of the scoop.

With such a boom and scoop and appropriate rigging dirt may be excavated for 30 various purposes and deposited in carts or other containers with great facility. The ditching scoop is of a character whereby the scoop is caused to actively travel toward the machine either in the line of travel of the machine as a whole or transversely 35 thereof, and when the scoop is full it is lifted, mouth end upwardly, from the excavation being formed, and then by swinging the boom in a suitable direction the scoop is brought over the container and 40 released, whereupon the load, then overbalancing the scoop, causes the latter to invert so that the mouth end is downward and the load will naturally gravitate from the scoop into the container.

45 The invention will best be understood from a consideration of the following detailed description taken in connection with the accompanying drawings forming a part of this specification, with the understanding, however, that the invention is not confined to any strict conformity with the showing of the drawings but may be changed and modified so long as such changes and

modifications make no material departure from the salient features of the invention as expressed in the appended claims.

In the drawings,—

Figure 1 is a front elevation, with some parts more or less diagrammatically shown, of an excavating machine with the boom and scoop associated and illustrating in full and dotted lines certain positions of the parts.

Figure 2 is a side elevation of the boom and scoop and some associated parts, with the scoop raised above the ground level.

Figure 3 is a vertical section through the scoop, and the ditcher stick, the drawing being on a larger scale than the preceding figures.

Figure 4 is an elevation of the structure 70 shown in Fig. 3 and viewed from the right hand side of Fig. 3.

Figure 5 is a section on the line 5—5 of Fig. 2.

Referring to the drawings, there is shown 75 an excavating machine A which may be of known form and mounted upon wheels 1 for facilitating transportation from place to place. A column 2, shown in Figs. 1 and 2, may be taken as illustrative of the forward 80 end of the machine and supporting by means of vertically aligned pivots 3 and brackets 4, 5, a column or mast 6 in which are mounted sheaves 7, 8. The column 6 by the bracket 5 at the lower end thereof carries 85 one end of a boom 9, which latter may be made of channel formation, but the particular construction of the boom is not necessary to an understanding of the invention, and needs, therefore, no particular description. 90 At the outer end of the boom extension plates 10 carry a ditcher stick 11, shown more particularly in Figs. 3 and 4, as formed of side bars 12 which may be of channel material joined where needed by cross bars 95 13. At one end the stick 11 is widened and terminates in legs 14. The compound or wide ditcher stick shown has an advantage over a single ditcher stick, in that, being considerably wider than the single stick, it has a long bearing, thus preventing the stick from twisting or buckling over to one side. The give of a single ditcher stick under side strains prevents the cutting of a truly perpendicular trench and, therefore, tending to 100 undercut the sides of the ditch and possibly

make them cave. At the other end the side bars 12 carry a shaft or spindle 15 on which is mounted a sheave 16. To stiffen the ditcher stick, cross members 17 may be employed. The boom 9 is connected to the side bars 12 near the sheave 16 by a shaft or spindle 18 traversing the plates 10 and thereby constituting a pivot connection between the boom and stick. At that end of the stick 11 remote from the sheave 16 the side bars 12 carry trunnions 19 journaled in straps 20 fast to the side walls of a shell 21 of a scoop B. The straps 20 are riveted or otherwise secured to the side walls of the scoop. These straps receive the trunnions 19 in an axis approximating the center of gravity of the scoop crosswise of the latter. The scoop has a bottom plate 22 and a top plate 23, which latter constitutes a continuation of the bottom plate and is cut away or slotted as shown at 24 and is there traversed by the side bars 12 of the ditcher stick. The slots 24 permit rocking of the ditcher scoop about the axis of the trunnions 19 through an arc approximating 90°, whereby the scoop at one limit of its travel about its axial support has its bottom approximating the horizontal, and at the other limit of its movement the scoop is approximately upright with the bottom 22 substantially vertical. The axis of the trunnions 19 is well back in the scoop and at a considerable distance from the front or open end of the scoop so that when the scoop is filled with dirt, with the bottom horizontal, the scoop is overbalanced by the load toward the mouth end.

The scoop, which is usually made of sheet metal of suitable gage, may be stiffened by angles 25 wherever deemed necessary. At the mouth end of the bottom 22 of the scoop there is provided a plate 26 constituting a lip plate for the mouth end of the scoop, and this lip plate and mouth end of the scoop are armed by suitable teeth 27 facilitating the digging action of the scoop. Furthermore, the side plates of the scoop at the mouth end are provided with trimming teeth 28 so that the scoop may be employed to dig a trench as wide as the scoop, or to widen such a trench by a repetition of the digging action with the dirt of the side walls of the formed trench attacked by the trimming teeth 28.

On opposite sides of the scoop are beveled latch plates 29, and each side bar 12 is provided with a lock pin 30 mounted to move through straps 31 into and out of the path of the latch plates 29. Each pin 30 is provided with a stud 32 engaged by the forked end 33 of a rock arm 34 fast to a rock shaft 35 journaled on and extending between the two side bars 12 in relatively close relation to the ditcher scoop. Fast to the rock shaft 35 is a latch lever 36, to the end of which, remote from the shaft 35, there is attached

a trip line 37 continued to some convenient point of manipulation, say upon the body of the machine A.

The lever 36 is constrained in the direction to hold the lock pin 30 in engagement with the latch plate 29 by a retractile spring 38 carried by a slidale bolt 39 mounted on one of the side bars 12.

Each side plate 21 at the mouth end of the scoop or bucket is provided with an anchor plate 40, the two anchor plates having pivoted thereto the leg ends of a bail 41 to which there is attached a clevis 42 receiving one end of a pulling line 43 carried over a sheave 44 on the boom 9 and under the sheave 8 and then over another sheave 45 to an appropriate part of the machinery mounted on the excavating machine A, but requiring no special discription.

The sheave 16 is engaged by a line 46 which, in the particular showing of the drawings, is connected at one end to one end of a link 47, the other end of which link is pivotally connected to the upright 3 so as to turn in the axis of the upright 3 and of the boom 9. The other end of the line 46 is carried about the sheave 7 and thence about the sheave 45 or a companion sheave to the operating machinery on the excavator A.

In order to steady the excavating machine it is provided with bracing jacks or outriggers 48, permitting the boom 9, and parts carried thereby, to be swung to one side of the line of travel of the excavating machine or in line with such line of travel.

If it be assumed that the excavation is to be such as a cellar excavation or the like, the excavating machine is properly located and the bracing jacks are placed, whereupon the boom is so located as to extend to one side of the excavating machine to position the excavating scoop over that part of the proposed cellar-way distant from the excavating machine, the boom being raised and the ditcher stick projecting outwardly from the boom, say to as near a horizontal line as the structure will admit. If the ground be hard or if for some other reason considerable force must be used in order to start the excavation, the parts are so adjusted that the scoop itself while latched to the ditcher stick is in substantially pendant relation to its axis 19. If, now, the boom be swung about its pivotal axis of connection with the block 5 it will approach the ground similarly to a pick or hoe. This is accomplished by a suitable manipulation of the line or cable 46, and the ground is attacked in much the same manner as it is by means of a pick in the hands of a workman.

Such action will cause the scoop to force its way into the ground until the hard top pan is broken up and the scoop is enabled to enter the softer dirt below.

This same procedure may be followed where it is needful to disengage rocks embedded in the dirt. The position of the boom and ditcher stick in the preliminary operation is shown in Fig. 1 in dotted lines, on the left hand side thereof.

To continue the excavation, the pulling line 43 is manipulated and the elevating line 46 is slacked, thus permitting the ditching scoop to be dragged into the ground and toward the ditching machine, until finally an excavation similar to that shown at the left hand side of Fig. 1 is produced. From time to time it is necessary to move the scoop with the disturbed dirt lodged therein and deposit the excavated dirt in a receptacle such as a cart, indicated in dotted lines 49 at the right hand side of Fig. 1. In moving the scoop toward the excavating machine by means of the pulling line 43, the toothed or digging end of the scoop is drawn toward an upright position, thus holding the gathered dirt in the scoop. When the boom is sufficiently elevated with the load therein, the boom is swung toward the cart 49 until over it, the boom being lifted sufficiently for the purpose. Ultimately the trip line 37 is manipulated, thus releasing the scoop from its latched position with respect to the ditcher stick 11, whereupon the weight of the dirt and the scoop will overbalance it and the scoop will turn to a pendant dumping position, shown in dotted lines at the right hand side of Fig. 1, thereby most effectively discharging the load without necessitating so great an elevation as has customarily been the case, or limiting the structure to the employment of containers of low elevation.

Unless the scoop attains a substantially perpendicular position in dumping, soft material will build up in the corners of the scoop and so fail to dump clean. By hinging the scoop at its extreme end to the ditcher stick, the weight of the scoop, which may be from 500 to 600 pounds and the weight of the load, which may reach 2000 to 2500 pounds, is carried by the spring latch or trigger, making such an arrangement very hard to release by a hand tug rope, such release often times requiring a second or third jerk upon the rope. This trouble may be overcome by centrally pivoting the scoop, that is, at or substantially at its center of gravity, whereby the weight upon the latching device is insignificant. This is important, as for instance, when the scoop is rapidly swung over a comparatively small car or truck to dump the scoop. The operator desires to dump the scoop as the latter is over the car and moving. Should the trigger fail to respond to the operator's pull on the tug line, the contents of the scoop will then miss the car and the load of the scoop will spill.

By hanging the scoop at about its center of gravity it need not be lifted as high by two or three feet as heretofore, in order to dump into the receptacle at a given height. Such a scoop hung centrally or approximately so, will automatically return to the position for dumping.

The scoop of the invention has the lifting sheave journaled directly in the top end of the bifurcated ditcher stick, thus contributing materially to the steadiness of the structure.

What is claimed is:

1. In an excavating machine, a swinging boom mounted for sidewise and up and down movements, a pivoted scoop having an axis of movement at approximately the center of gravity of the scoop, said scoop having one end open to constitute the mouth of the scoop and the other end closed and a suspension stick for the scoop carried near one end by the boom and at the other end carrying the scoop at approximately the center of gravity of the latter, the closed end of the scoop being curved on the axis of said center.

2. In an excavating machine, a swinging boom mounted for up and down movements, a pivoted scoop having an axis of movement at approximately the center of gravity of the scoop, the end of the scoop remote from the mouth being curved on the axis of the approximate center of gravity of the scoop, the mouth of the scoop facing toward the machine, a swinging suspension stick for the scoop carried near one end by the outer end of the boom and capable of swinging in a plane lengthwise of and beyond the boom and forming a continuation of the latter, means for pivotally mounting the scoop on its axis to the lower end of the stick, and latching means carried by the stick and engaging the scoop to hold the latter from movement on its axis.

3. In an excavating machine, a swinging boom mounted for up and down movements, a pivoted scoop having an axis of movement at approximately the center of gravity of the scoop, the end of the scoop remote from the mouth being curved on the axis of the approximate center of gravity of the scoop, the mouth of the scoop facing toward the machine, a swinging suspension stick for the scoop carried near one end by the outer end of the boom and capable of swinging in a plane lengthwise of and beyond the boom and forming a continuation of the latter, means for pivotally mounting the scoop on its axis to the lower end of the stick, latching means carried by the stick and engaging the scoop to hold the latter from movement on its axis.

4. In an excavating machine, a swinging boom mounted for up and down movements, a pivoted scoop having an axis of movement at approximately the center of gravity of the scoop, the end of the scoop remote from the mouth being curved on the axis of the approximate center of gravity of the scoop, the mouth of the scoop facing toward the machine, a swinging suspension stick for the scoop carried near one end by the outer end of the boom and capable of swinging in a plane lengthwise of and beyond the boom and forming a continuation of the latter, means for pivotally mounting the scoop on its axis to the lower end of the stick, latching means carried by the stick and engaging the scoop to hold the latter from movement on its axis, a hoisting line connecting with the stick for elevating both the stick and boom, a trip line connecting with the latching means for releasing the same, and a hauling line connecting with the mouth end of the

- 4 scoop for drawing the latter inwardly toward the machine when filling the scoop.
- 5 4. In an excavating machine, a pivoted boom mounted to move up and down, a swinging suspension stick for the scoop 70 pivotedly connected to the outer end of the boom and extended above and below the latter, said stick being capable of swinging in a plane lengthwise of and beyond the 10 boom and forming a continuation of the latter, a scoop pivotedly connected to the lower end of the stick and having its open end facing the machine when in loading position, said scoop having its open end facing downwardly toward the ground when the stick is 15 extended outwardly from the boom, releasable means engaging the scoop for holding the scoop from movement on its axis, a hauling line connected to the open end of the 20 scoop for drawing it toward the machine to fill the same, and a line connected to the extended upper end of the stick, said line serving both as a hoisting line for elevating the boom and stick and for moving the stick 25 carrying the scoop outwardly, said hoisting and hauling lines being co-ordinated in operation to present the open end of the scoop facing the ground and to draw the scoop toward the machine for filling the same.
- 30 5. In an excavating machine, a pivoted boom mounted to move up and down, a swinging suspension stick carried near one end by the boom and capable of swinging in a plane lengthwise of the boom, so as to be 35 extended beyond the boom in a substantially horizontal position, a centrally pivoted scoop carried by the end of the stick remote from the boom, said scoop having its open end facing inwardly toward the machine when 40 loading and facing downwardly toward the ground when the stick is extended outwardly, said stick having a sheave at the end remote from the scoop, and a line extending about the sheave for causing swinging movements 45 of the stick with relation to the boom and also for raising and lowering the boom, the scoop being also provided with a hauling line connected to the open end of the scoop.
- 50 6. In an excavating machine, a swinging boom mounted for up and down movements, a ditcher stick pivoted to the outer end of the boom and extending above and below the same, means for mounting a sheave to the upper end of the stick, a hoisting line passed 55 about the sheave for raising and lowering the boom and stick, and also for moving the stick outwardly lengthwise of the boom, said stick being movable to a substantially horizontal position beyond the boom, a scoop 60 mounted at the lower end of the stick and having its open end facing the machine when in loading position, said open end carrying digging teeth and facing downwardly toward the ground when the stick is in its extended position, and a hauling line connected 65 to the open end of the scoop for drawing it toward the machine to fill the same, whereby the coaction of the hoisting and hauling lines causes excavating movements of the scoop and its elevation and lowering.
7. In an excavating machine, a swinging boom mounted for up-and-down movements, a ditcher stick pivoted to the outer end of the boom and extending above and below the same, a hoisting line connected to the top of the ditcher stick for raising and lowering the boom and stick and also for moving the stick outwardly lengthwise of the boom, said stick being movable to an extended position beyond the boom, a scoop mounted at the lower end of the stick and having its open end facing the machine, when in loading position, said open end carrying digging teeth and facing downwardly toward the ground when the stick is in its extended position, and a hauling line connected to the open end of the scoop for drawing it toward the machine to fill the same, whereby the coaction of the hoisting and hauling lines causes excavating movements of the scoop and its elevation and lowering.
8. An excavator provided with a boom mounted for oscillation about an upright axis and for rising and falling movements, a ditcher stick pivoted to the boom to rock 95 toward and from the boom lengthwise of the latter, and a scoop pivoted to the stick at the end of the latter remote from the boom and movable about its pivotal axis in a plane lengthwise of the boom, the stick having means for actuating it and the end of the scoop toward the pivoted end of the boom having means for actuating it, whereby the co-action of the two actuating means causes excavating movements of the scoop and the elevation and lowering of the scoop, the stick and scoop having co-acting latch means for securing them in fixed relation to each other, and manipulating means whereby the scoop may be unlatched from the stick.
9. In an excavating machine, the combination with a pivoted boom, a ditcher stick pivoted at a point between its ends to the outer end of the boom and formed of a pair of side bars rigidly connected together, a sheave mounted at and between the upper ends of the side bars, and a scoop pivotally connected to and between the lower ends of the side bars.
10. In an excavating machine, the combination with a pivoted boom, of a ditcher stick composed of a pair of side bars rigidly connected together, a sheave mounted between and connected to the upper ends of the side bars, means for pivotally connecting the side bars of the ditcher stick below the sheave to the end of the boom, said side bars diverging outwardly at the bottom, a scoop pivotally connected to and between the lower ends of the ditcher stick, and latching mech- 120 125 130

anism for holding the scoop from pivotal movement.

11. In an excavating machine, the combination of a divided and braced ditcher stick, 5 a pivoted operating boom carrying the ditcher stick, a sheave on the ditcher stick, a pivoted scoop having its axis of pivoting substantially coincident with the center of gravity of the scoop, and a spring-controlled 10 latching means for the scoop.

12. In an excavating machine, a revolute column, a pivoted boom connected to the column to move therewith and having side- 15 wise and up and down movements, a ditcher stick pivotally connected to the outer end of the boom and extended above and below the same, a scoop having side walls, an end wall, a bottom wall and an open end, the latter having digging teeth and facing toward the 20 machine when the scoop is in filling position, means connecting the stick to the scoop in such a position that when the scoop is loaded the center of the weight thereof is in axial alinement with the ditcher stick, 25 a hoisting line connected at one end to the machine and passed about a sheave connected to the upper end of the ditcher stick and then leading back to the machine, said line being operable for raising and lowering the boom and stick and for moving the stick outwardly lengthwise of the boom, said stick being movable to a substantially horizontal position beyond the boom, in which position the scoop hangs pendently from 30 the end of the stick with its open end facing downwardly toward the ground, a hauling line connected to the open end of the scoop, then passed about a sheave mounted on the boom, and also leading back to the machine, 35 said hoisting and hauling lines being coordinated in operation to present the open end of the scoop in a substantially perpendicular position with relation to the ground and to draw the scoop toward the machine 40 for filling the same.

13. In an excavating machine, the combination with a ditcher stick formed of two connected side bars, a scoop pivoted to the ditcher stick and provided at opposite sides 45 with latch plates, lock pins mounted on the ditcher stick and adapted to move into and

out of the path of the latch plates, a rock shaft journaled on the ditcher stick and having a rock arm engageable with the lock pins, a latch lever mounted on the rock 55 shaft, a spring for holding the lock pins into engagement with the latch plates, and means connected with the latch lever for operating the same.

14. In an excavating machine, the combination with a ditcher stick composed of two side arms connected together in rigid relation, a scoop, means for pivotally connecting the lower ends of the side arms to the outer sides of the scoop at a point between the top 60 and bottom and front and rear of the scoop, latching mechanism carried in part by the ditcher stick and in part by the scoop, said latching mechanism including a latch plate on the top of the scoop, a lock pin mounted 65 on the ditcher stick and engaging the latch plate, and means for actuating the lock pin to release the scoop.

15. In an excavating machine, the combination of a pivoted ditcher stick, an operating sheave at one end of the stick, a pivoted scoop at the other end of the stick, a boom carrying the pivoted stick, a lifting cable extended about the sheave, a hauling cable connected to the nose end of the scoop, 75 and a latch for holding the scoop temporarily in fixed relation to the ditcher stick, whereby the ditcher stick may be held in a substantially horizontal position with the digging end of the scoop substantially perpendicular to the ground and to the ditcher stick and with the scoop held in said relation to the ditcher stick by the latch.

In testimony, that we claim the foregoing as our own, we have hereto affixed our signatures.
